Attorney

UNITED STATES PATENT OFFICE.

WALLACE E. WALDEN, OF DOMINGO, NEW MEXICO.

FEED FUEL FOR EXPLOSION ENGINES.

Application filed July 6, 1922. Serial No. 573,228.

To all whom it may concern:

Be it known that I, WALLACE E. WALDEN, a citizen of United States, residing at Domingo, in the county of Sandoval, State of New Mexico, have invented certain new and useful Improvements in Feed Fuel for Explosion Engines; and I do hereby declare the following to be a full, clear, and exact description of the invention, such as will enable others skilled in the art to which it appertains to make and use the same.

The object of the invention primarily is to provide a feed fuel means whereby the admission of moisture or of liquid fuel such as unvaporized gasoline to the combustion chambers of the cylinders of the motor may be prevented, and hence specifically interpose an obstruction in the path of the film of liquid fuel due to deposit by condensation on the walls of the fuel feed tube, and which, due to the impulse of the vapor passing through the feed tube, tends to creep toward and ultimately enter the cylinders where it is objectionable by reason of causing a carbon deposit through incomplete combustion; and furthermore to provide a fuel feeding device for motors whereby an additional supply of air may be introduced into the mixture adjacent to the point of supply of the fuel to the motor cylinders, and to construct such means in the form of an attachment which may readily be applied to a motor of the conventional type without involving any modification in the construction thereof; and with these general objects in view, the invention consists in a construction, combination and arrangement of parts of which a typical embodiment is illustrated in the accompanying drawings, wherein:

Figure 1 is a sectional view of a motor fuel feeding tube, for conveying mixture from the carburetor or other source of supply to the motor cylinders, equipped with a feed mechanism embodying the invention.

Figure 2 is a section taken at right-angles to the plane of Figure 1.

Figure 3 is a detail view of the attachment embodying the invention detached from the feed tube.

Figures 4 and 5 are sectional views taken longitudinally and parallel with the planes of the side surfaces of the attachment and viewing the same respectively in opposite directions.

Figure 6 is a detail sectional view on the

plane of Figure 1, showing the means whereby the accumulation of liquid is removed.

The device embodies a baffle 10 of annular form with a concaved surface presented toward the direction of progress of fuel 60 through the feed tube 11, used in the conventional type of internal combustion engines, preferably at a point near the junction of said feed tube with the intake manifold 12 of the motor, as for example, at the joint 65 between the feed or intake tube and said manifold, and this baffle may be carried by or formed as a part of a plate or gland 13, of dimensions corresponding with the coupling plates 14 and 15, by which the feed 70 or intake tube is attached to the intake manifold, for interposition between said coupling plates as shown in Figures 1 and 2, so that the plate or gland 13 may be secured in position by the bolts 16 which are ordinarily 75 used to connect said coupling plates.

This baffle serves to obstruct or interrupt the passage along the walls of the feed or intake tube toward the intake manifold of the film of gasoline or other fuel which is 80 deposited in a condensed or liquid form upon said walls and which under ordinary conditions is caused to creep toward the cylinders of the engine and ultimately enter the same by reason of the impulse due to 85 the passage of vapor consisting of the mixture from the carburetor to the cylinders. The baffle serves to collect this liquid and at the same time to restrict or reduce the passage through the intake tube so as to increase the rapidity of the progress of the mixture at that point, and hence increase the efficiency or completeness of the mixture.

Taking advantage of the increased rapidity of movement of the mixture at this point of reduction in the intake tube, it is also preferred to provide a means whereby an additional supply of atmospheric air may be combined with the mixture as a means of 100 economizing in the consumption of fuel, and to this end the plate or gland 13, which for convenience in reference may be described as a mixer gland, is provided with a transverse channel 17 consisting in the construction illustrated of a tube arranged in spanning relation with the opening 18 in the gland and fitted at its extremities in transversely registering bores in the gland plate, with a jet opening or orifice 19 formed in the 110

inner wall thereof, or in that wall facing the intake manifold and at or about the center of the opening 18, and hence about in the plane of the annular baffle 10, where the vapor passes through the intake tube and attains its highest velocity. One end of the conveyor should be closed as indicated at 20, while the other end is in communication with a channel 21 cored in the mixer gland 10 and extended to an inlet port 22 near one end thereof and within the contour of the gland, so as not to be obstructed by the arrangement of the coupling plates 14 and 15, which are in contact with the opposite side surfaces thereof.

In practice the baffle as will be understood serves to interrupt and direct the film of liquid fuel approaching the motor cylinders and at the same time acts as a reducer, while the conveyor which is disposed in spanning relation with the opening in the mixer gland and which registers with the intake or feed tube, affords a means of supplying an additional proportion of air to the mixer under the influence of suction at the point of highest velocity of mixture in its passage to the motor cylinders, with the result of presenting the mixture in economical proportions and in practically a dry state to the combustion chambers.

The accumulation of liquid fuel intercepted by the baffle 10 and collected at the lower end of the tubular channel 17 is removable by suction through the said tube by way of a minute orifice 23 formed in the tube 17 in communication with the chamber formed by the concaved surface of the baffle, so that the liquid fuel is drawn to the center of the tube 17 through the air suction entering at 22 and is discharged through

the jet or opening 19 into the center of the column of vapor traversing the feed tube 11. The liquid accumulation therefore is discharged into the column of gas approaching the manifold and is atomized to avoid disadvantages incident to the induction of liquid fuel into the cylinders as hereinbefore explained.

What is claimed is.

1. A fuel intake tube for explosion motors having an annular inwardly projecting baffle or flange for interrupting the creeping of liquid on the wall of the tube and a transversely spanning conductor having an orifice presented in the direction of the movement of fuel through said tube, said conductor being further provided with a second orifice or inlet in communication with the space in rear of said baffle or flange. 55

2. An attachment for the fuel intake tube of an explosion motor consisting of a gland having an opening registering with that of the tube and being further provided within the contour thereof with a longitudinally extending channel, an annular baffle or flange for interrupting the creeping of liquid on the wall of the tube, and a transversely spanning conductor having an orifice presented in the direction of the movement of fuel, the said conductor having one of its ends intercepting the channel, and being further provided with a second orifice or inlet in communication with the space in rear of said baffle or flange. 65

In testimony whereof, I affix my signature, in the presence of two witnesses. 75

WALLACE E. WALDEN.
